GOLF GAME DEVICE

Richard M. Hall, 808 W. 31st St., Richmond, Va.
Filed Nov. 21, 1957, Ser. No. 697,837
4 Claims. (Cl. 273—181)

This invention relates generally to a golf game device and more particularly to a golf game device for use in conjunction with an ordinary golf club and ball.

Golf enjoys a widespread popularity which is based in part upon the fact that players can exercise and relax in the fresh air. In addition, it is not a game for only one age group but for all age groups. However, the fact that a permanent and meticulously cared for outdoor course is an essential feature of the game is a distinct disadvantage. Neither land nor money is plentiful enough to permit the construction and maintenance of enough courses to satisfy the public demand.

My invention is designed to provide outdoor fun and relaxation as well as exercise for people of all ages by simulating the game of golf without using or requiring a permanent landscaped course. Thus the dual problems of land and money are almost completely eliminated and hence many people can use my invention who would never have an opportunity to play any game even remotely resembling golf.

Broadly, my invention is a series of stands, preferably nine, spaced about the playing area; each stand comprising a base resting upon the ground and two uprights extending vertically from the ends of the base. Pivoted about the uprights are numbered score indicators and a gate or stand marker. One side of the base will also comprise a ramp to allow a rolling ball to pass through the scoring area.

The invention will be more fully understood by reference to the accompanying drawings illustrating a preferred embodiment of the invention, of which:

FIG. 1 is a perspective view of the manner in which the apparatus may be used;

FIG. 2 is a partial sectional front view of the apparatus shown in FIG. 1;

FIG. 3 is a partial sectional side view of FIG. 2; and

FIG. 4 is a sectional view taken along 4—4.

As shown in FIG. 2 each gate comprises a base portion 1 which rests upon the ground and maintains an entire gate in the proper vertical position. One side of the base portion comprises a ramp 2 up which a ball may roll if hit along the ground and not through the air. Set into each end of the base portion are molded sockets 3 adapted to receive and hold firmly in place upright members 4. Though held securely in position the uprights 4 are readily removable for ease in the disassembling and moving of the gates. Pivoted about the uprights are score indicators 5 comprising a cylinder portion 6 which encompasses an upright in frictional engagement and a "flag" portion 7 extending horizontally from the cylinder portion 6 almost one-half the distance between the two uprights 4. The flag portions 7 of oppositely situated indicators will not therefore touch each other. The score indicators 5 are pivoted about the uprights so that if a ball should strike an indicator, the indicator will swing to the rear as shown in FIG. 4. The score indicator so struck will remain in the displaced position, thereby aiding in scoring, by reason of the frictional engagement the cylinder portion 6 with the upright. Also pivoted about the uprights are cylindrical sleeves 8 which are easily removable like the score indicators 5. The sleeves 8 and score indicators 5 are slipped onto the uprights so that sleeves and score indicators alternate in varying combinations with each other from gate to gate, for example, one pattern being as shown in FIG. 2. A gate indicator 9 is put on the uprights in the same manner as the score

2

indicators are after the score indicators and sleeves are on. Each gate indicator bears a different number to designate the sequence of play and to permit scoring for each gate.

5. To be used the gates must first be spaced about the playing area. The arrangement may be any that is desired by the players, but it should be such that play will progress in a natural sequence from gate number 1 to gate number 2 and on to gate number 9. The ball is placed 10 on the ground three or four yards from the first gate. The first player then attempts to hit the ball through the gate without hitting any part of the gate. If the ball does actually pass through without touching a portion of the gate, the score for that player for that gate will be 15 the number of actual strokes used. Should the ball strike a score indicator thereby forcing it to swing to the rear to permit the ball to continue on its flight, the score of the player includes the actual strokes plus the number written on the displaced score indicator. Thus, each 20 player who causes the displacement of a score indicator in effect suffers a penalty. Accurate scoring is assured because a score indicator moved by the impact of a ball will remain in a displaced position due to the frictional engagement of the score indicators with the uprights. 25 At the end of the game the scores for each gate may be added to give a total "medal" score for each player, the lowest total winning as in golf. Also as in golf the lowest score for each gate is the winning score for that gate, and if "match" play is simulated, the winner would be that 30 player winning the most gates.

By changing the arrangement of the score indicators, which is done by varying the number and position of sleeves and score indicators on the uprights, each gate offers a new challenge to, and new opportunities for improving the players' skill. However, a player may prefer the easy way of getting the ball through the gate by hitting the ball along the ground so that it will roll up the ramp and through the gate. To encourage players to try for "a gate in one" the score indicators are so advantageously arranged so that a rolling ball will always displace a score indicator thereby causing the player to suffer a "penalty" every time.

Additional rules can be devised by those using my invention to reflect their personal preferences, e.g., penalties to be incurred when a ball hits a non-movable part of the gate, boundary lines, when the player can move the ball back to the playing area and what additional strokes will be added to his score by so moving the ball.

The entire gate may be constructed from any solid material that can withstand the impact of moving golf balls. However, since one feature of my invention is the portability of the gates assembled or disassembled, a lightweight material would be preferred. My invention would not be affected by the choice of materials 55 used.

While one embodiment of the invention has been shown and described in detail, it will be understood that this is illustrative only and is not to be taken as a definition of the scope of the invention, reference being had for this 60 purpose to the appended claims.

I claim:

1. Golf game apparatus comprising a series of gates, each of said gates comprising in turn a base portion one side of which is a ramp; two tubular upright members 65 extending from said base portion, a plurality of randomly spaced score indicators pivoted about said upright tubular members so as to be moved upon impact, each of said score indicators being subject to friction drag to retain said score indicator in any displaced position 70 it might assume following impact, said score indicators having a horizontal length of less than one-half the distance between said tubular uprights, a plurality of sleeves

fitted about each upright for separating some of said score indicators mounted on said uprights; each of said score indicators and said sleeves being removable to permit a change in the arrangement of score indicators and sleeves on the gate, and a removable gate indicator fitted to the free ends of said tubular uprights.

2. A gate for a golf game comprising a base portion one side of which is a ramp; two tubular upright members extending from said base portion, a plurality of randomly spaced score indicators pivoted about said upright tubular members so as to be moved upon impact, each of said score indicators being subject to friction drag to retain said score indicator in any displaced position it might assume following impact, said score indicators having a horizontal length of less than one-half the distance between said tubular uprights, a plurality of sleeves fitted about each upright for separating some of said score indicators mounted on said uprights; each of said score indicators and said sleeves being removable to permit a change in the arrangement of score indicators and sleeves on the gate, and a removable gate indicator fitted to the free ends of said tubular uprights.

3. Golf game apparatus comprising a series of gates each of said gates comprising two tubular upright members, a plurality of randomly spaced score indicators pivoted about said upright tubular members so as to be moved upon impact, each of said score indicators being subject to friction drag to retain said score indicator in any displaced position it might assume following impact, a plurality of sleeves fitted about each upright for sepa-

5

rating some of said score indicators mounted on said uprights; each of said score indicators and said sleeves being removable to permit a change in the arrangement of score indicators and sleeves on the gate, and a removable gate indicator fitted to the free ends of said tubular uprights.

10

4. A gate for a golf game comprising two tubular upright members, a plurality of randomly spaced score indicators pivoted about said upright tubular members so as to be moved upon impact, each of said score indicators being subject to friction drag to retain said score indicator in any displaced position it might assume following impact, said score indicators having a horizontal length of less than one-half the distance between said tubular uprights, a plurality of sleeves fitted about each upright for separating some of said score indicators mounted on said uprights; each of said score indicators and said sleeves being removable to permit a change in the arrangement of score indicators and sleeves on the gate, and a removable gate indicator fitted to the free ends of said tubular uprights.
